FILAMENT TABBING MACHINE

Dale L. Chubb, Williamsport, and Robert S. Hutchison, Montoursville, Pa., assignors to Sylvania Electric Products Inc., a corporation of Delaware
Filed Dec. 4, 1959, Ser. No. 857,467
21 Claims. (Cl. 29—25.2)

This invention relates to a machine for forming short lengths of wire with tabs on the ends thereof.

In some types of electron devices, such as electron tubes, a very thin electron emissively coated heater wire is used, which wire is fastened at its ends to lead-ins of the tubes. In order to secure a good electrical and strong connection between the wire and the lead-ins, it has been customary to crimp or weld short sections of wide material, known as tabs, to bared ends of the filament and to weld these tabs to the lead-ins of the device.

It is an object of the invention to provide a machine which shall form a flat ribbon of tab material into a bent form to enable it to embrace a filamentary material, cut off a section of such formed ribbon, apply the section to the filamentary material and weld the section thereto, then cut through the tabbed filamentary material intermediate the ends of the ribbon section to form filaments with both ends tabbed, and place the tabbed filaments in appropriate slots in a storage tray.

It is a further object of the invention to provide a filament tabbing machine capable of producing very small tabs of very thin material on very thin filaments.

Other objects will become apparent upon reading of the following specification and claims.

The invention will be understood by referring to the following specification, when taken in conjunction with the accompanying drawings in which:

FIG. 1a is a plan view of the left hand end of the machine, parts being broken away.

FIG. 1b is a plan view of the right hand end of the machine.

FIG. 2a is a front elevation of the left hand end of the machine with parts broken away.

FIG. 2b is a front elevation of the right hand end of the machine with parts broken away.

FIG. 2c is a view of a tabbed filament as made by the machine.

FIG. 3 is a section through a ribbon orientator taken on the line 3—3 of FIG. 1a.

FIG. 4 is a detailed front elevation of the centering device and an adjoining portion of a ribbon forming device.

FIG. 5 is a section through the ribbon centering device taken on the line 5—5 of FIG. 1a.

FIG. 6 is a horizontal section taken on the line 6—6 of FIG. 5.

FIG. 7 is a vertical section through the centering device taken on the line 7—7 of FIG. 6.

FIG. 8 is a horizontal section through a portion of the centering device taken on the line 8—8 of FIG. 7.

FIG. 9 is a section through the ribbon forming device taken on the line 9—9 of FIG. 1a.

FIG. 10 is a section taken on the line 10—10 of FIG. 1a looking into the ribbon feed drive mechanism.

FIG. 11 is a vertical section on the line 11—11 of FIG. 10.

FIG. 12 is a vertical section on the line 12—12 of FIG. 10.

FIG. 13 is a horizontal section on the line 13—13 of FIG. 10.

FIG. 14 is a section taken on the line 14—14 of FIG. 12.

FIG. 15 is a top view of the cutter head.

FIG. 16 is a section on the line 16—16 of FIG. 15.

2

FIG. 17 is a side elevation of the cutter head.

FIG. 18 is a front elevation of the cutter head.

FIG. 19 is a rear elevation thereof.

FIG. 19a is a fragmentary view showing a hanger.

5 FIG. 20 is a vertical section on the line 20—20 of FIG. 17.

FIG. 21 is a horizontal section on the line 21—21 of FIG. 17.

10 FIG. 22 is a top plan view of a cut off ribbon section transfer head.

FIG. 23 is a front elevation of the head.

FIG. 24 is a side elevation of the transfer head.

15 FIG. 25 is a second and other side elevation of the transfer head.

FIG. 26 is a section on the line 26—26 of FIG. 22.

FIG. 27 is a section on the line 27—27 of FIG. 24.

FIG. 28 is a section on the line 28—28 of FIG. 24.

FIG. 29 is a section on the line 29—29 of FIG. 25.

20 FIG. 30 is a rear elevation of the transfer head with parts in section.

FIG. 31 is a detail showing how the ribbon section is held by the jaws of the head prior to the transfer of the ribbon section.

25 FIG. 32 is a plan view of a welder for welding cut ribbon section and filament assemblies to secure the filament to the ribbon section.

FIG. 33 is a back view of the welder.

FIG. 34 is a front view of the welder.

30 FIG. 35 is a side view of the welder with parts broken away to expose otherwise hidden portions.

FIG. 36 is a section on the line 36—36 of FIG. 32.

FIG. 37 is a section on the line 37—37 of FIG. 34.

FIG. 38 is a section on the line 38—38 of FIG. 32.

35 FIG. 39 is a section on the line 39—39 of FIG. 35.

FIG. 40 is a plan view of ribbon section assembly holding tools.

FIG. 41 is a section on the line 41—41 of FIG. 40.

25 FIG. 42 is a view showing how a welding electrode is held.

FIG. 43 is a plan view partly in section of the assembly cut off head and associated mechanism.

FIG. 44 is a side elevation thereof.

FIG. 45 is an elevation of another side thereof.

40 FIG. 46 is a front elevation thereof, parts being shown in section.

FIG. 47 is a section on the line 47—47 of FIG. 45.

FIG. 48 is a section on the line 48—48 of FIG. 45.

45 FIG. 49 is a very much enlarged section on the line 49—49 of FIG. 46.

50 FIG. 50 is a plan view of a tabbed filament feed mechanism, parts being shown in section.

FIG. 51 is an elevation of the same mechanism with parts shown in section.

55 FIG. 52 is a view of the mechanism looking at it from the right of FIG. 51.

FIG. 53 is a section on the line 53—53 of FIG. 50.

FIG. 54 is a section on the line 54—54 of FIG. 50.

55 FIG. 55 is a plan view of a tabbed filament transfer mechanism.

60 FIG. 56 is an end view thereof.

FIG. 57 is a second end view thereof, parts being shown in section.

FIG. 58 is a section on the broken line 58—58 of FIG. 56.

65 FIG. 59 is a section on the broken line 59—59 of FIG. 58.

FIG. 60 is a section on the line 60—60 of FIG. 56.

FIG. 61 is a development of a cross over cam.

70 FIG. 62 is a diagrammatic layout of the valve, switch and cam control for the various parts of the machine.

FIGS. 63 and 63a together constitute a timing chart showing the timed relationship of parts.

In FIGS. 1a, 1b, 2a and 2b there are shown generally, the parts of the machine necessary to form the tabbed filament of FIG. 2c.

The tabbing ribbon 30 which is of the order of .002" thick and .020" wide, is fed from a spool, not shown, through a ribbon cleaning tank 32 which may be of any conventional form and over an idler roll 34. The ribbon is fed horizontally, flat side up, from the cleaning tank and over the idler roll 34 and is then fed through the bite of a pair of guide rollers 36 which effects a 90° rotation of the plane of the ribbon to bring the flat side thereof into a vertical plane.

Next, the ribbon is fed through a ribbon centering device 38 which centers the ribbon both laterally and vertically so as to be sure that the ribbon will be subsequently properly positioned to be bent by a forming head to a dihedral angle with equal arm lengths and of somewhat V shape with the opening of the V directed downwardly of the sheet in FIG. 1a or toward the reader in FIG. 2a. The feeding of the ribbon is accomplished by a ribbon feed head 42 which has means to releasably grasp the bent ribbon and which reciprocates longitudinally of the machine. The feeding head pushes the bent ribbon into the jaws of a cutting head 44 having relatively movable cutting knives 46, 47 and 49, FIGS. 15, 18, and 32, to effect cut-off of a length of bent ribbon. Prior to cutting-off, the ribbon had been advanced by the feed head 42, FIGS. 1a and 2a, to a position where the leading end was in position to be grasped by the jaws of a transfer and crimping head 48, FIG. 2a. The head 48 reciprocates transversely of the machine to transfer a cut-off section 50, FIG. 49, of bent ribbon from the line of ribbon feed, laterally, to a position where the ribbon overlies and underlies a filament 52.

The filament 52, in this exemplary form of the invention, is intended to be used as a directly heated cathode within an electron tube and comprises emissively coated identical sections 54, see FIG. 2a, alternating with identical bared sections 56 of the filamentary material. The filamentary material is drawn off from any convenient form of supply, as a roll, not shown. After a cut-off ribbon section has been crimped about a bared section 56 of the filament, the ribbon section is welded to the filament by welding jaws mounted on a welding unit 53.

The filament and welded-on ribbon section are next drawn through a cutting head 60 and over a transfer drum 62, FIGS. 1b and 2b, by a filament pulling head 64. The head 60 has jaws to grasp the ribbon while a pair of knives cut the ribbon diagonally across the width thereof to form the filament with a tab at each end as shown in FIG. 2c, the cut filament being retained in a slot in the transfer drum after the filament has been cut. The drum indexes on a horizontal axis to carry the tabbed filament around until it is at the bottom of the drum, suction means holding the filament to the drum. When the tabbed filament is at its lowest position on the drum, the suction is cut off to cause the filament to fall into a slot in an indexable tray 68, FIG. 56. The head 64 is reciprocated longitudinally of the machine to a position where its jaws enter between the jaws of the cutting head 60 to grasp the tabbed end section of the string of ribboned filament and back to a position to the right of the transfer drum, as viewed in FIG. 2b.

Details of the specific parts of the mechanism will now be described.

The tabbing mechanism is mounted on a table 100, FIG. 2a, with a main frame 102 supported above the table by standards 104 and 106. The ribbon cleaning tank 32 and idler roll 34 are supported by a bracket 108 attached to the frame 102. On top of the frame 102 is a casting 110 to suitably mount various parts of the mechanism, as will be described. Fastened to the side of the casting 110 is a block 112, surmounted, as shown in FIG. 3, by a pair of slides 114 and 116 each mounting a roller 36 to guide the ribbon, the slide 114 being ad-

justable through the intermediary of a headed screw 120 bearing against a vertical web 122 of the block 112 and threaded into the slide, and the slide 116 being adjusted by a set screw 124 threaded through the projection and bearing against the slide. The two slides are locked by a fastening screw 126 threaded into the horizontal web 128 of the bracket.

As the ribbon material is drawn through the rolls 36, it is orientated through 90° to a position where its broad dimension is vertical. The ribbon is then pulled through the centering device 38. The centering device is illustrated in detail in FIGS. 4 to 8. It comprises a fixed blade 132, FIG. 5, mounted on a slide 134 adjustable longitudinally in a slot in a block 135 and held thereon by a cap plate 136, and a cooperating blade 137 mounted on a slide 138 in turn mounted in a recess in a block 139 and held therein by a cap plate 140 held to the block 139 by screws 143. The block 139 is fastened to a plate 142 by screws 147, FIG. 4, threaded into the plate 142. The plate 142 is held to the journal 144 by a pair of springs 145 reacting between the heads of the screws 149 and a pair of washers 146 bearing against the plate 142.

The screws 149 pass freely through the plate 142 to allow for vertical displacement thereof under control of a conically pointed screw 152 adapted to cooperate with a flared recess 153 in the journal 144. While adjusting screw 152 controls the raising and lowering of the blade 137 and of a pair of vertical centering fingers, as will be described, other means are provided for raising and lowering the blade 132. Raising and lowering of the blade 132 is effected by placing suitable shims beneath the block 135, the shims being fastened to the journal 144 by screws 156 passing through the block 135 and the shims and threaded into the journal. The limit of separating motion of the blades 132 and 137 is under control of adjustable limit screws 158 and 160 threaded into the parts fast with the blocks 135 and 139 respectively and abutting the ends of slides 134 and 138. A tightening up screw 161, FIG. 7, is also provided to maintain the slide 134 against the screw 158.

Vertically slidably mounted in the block 139 are the plates 162 and 164, FIG. 5, for centering the ribbon vertically with respect to the ribbon forming tool and which tool lies adjacent to the centering device. The plate 164, at its upper end, has a horizontal edge 166 to underlie the length of ribbon, and the plate 162 has a ledge 168 adapted to overlie the ribbon, the plate 162 being apertured at its upper end to permit free entry of the blade 132 toward the ribbon. The two plates are moved in opposition to each other by a device comprising a disc 170 and two pins 172 and 174, FIGS. 5, 6 and 7, eccentric of the disc, the pin 174 being longer than the pin 172 to extend through a slot in plate 164 and into a laterally elongated slot in plate 162. The short pin 172 extends into a laterally elongated slot in plate 164. The edge 166 and ledge 168 are urged toward each other by a torsion spring 176 mounted on a pin 178 integral with the disc 170 and journaled in the block 139. The torsion spring reacts between a cap plate 180 fastened to the block and a knurled finger piece 181 fixed to the pin 178 by a set screw 182. Thus the plates 162 and 164 may be easily separated by finger manipulation of piece 181 for insertion of a new length of ribbon between the fixed lateral adjusting blades 132 and 137. The vertical plates 162 and 164 are self centering for any width of ribbon and no adjustment for different ribbon tolerances is therefore necessary.

After the ribbon is positioned vertically and laterally as described, it is drawn through the forming device which is subsequently operated to form the ribbon into V shape. The forming device is illustrated in sectional detail in FIG. 9. The block 135 is fastened to the journal by screws 184 and is provided with a guide for a slide 186, the guide being closed off by a cap plate 188 suitably fastened to the block 135 to provide an area within which the slide may reciprocate. At the left hand end, FIG. 9,

the slide 186 carries a pair of forming tools 189 and 190, suitably recessed into one another to prevent shift, the tools being held to the slide by screws 192. Each of the operative ends of the tools has affixed thereto a hard insert 194 which form a V indentation where the inserts engage the ribbon. A cooperating hard insert 196 with a V-shaped tip extends opposite the inserts 194 and is fixed in its tool 198. The tool 198 is fixed on a vertically shiftable plate 200 which is pressed against the journal 144 and shiftable thereon by means of a screw 201 in a manner similar to the shifting of plate 142. Upstanding from the block 135 is a thrust pin 202 and reacting against the pin and the end wall 204 of a recess in the slide 186 is a spring 206, tending to move the slide to the right and therefore tending to separate the forming inserts 194 and 196. A link 208 under control of a cam on a cam shaft serves to move the slide and the insert 194 in a direction to cause the ribbon, positioned on edge between the inserts, to be given a V formation.

The journal 144, see FIG. 12, is provided with a bushing 210 within which lies a longitudinally slidable hollow shaft 212. An oscillatable shaft 214 is journaled in end bushings 216 within the hollow shaft and moves longitudinally with the hollow shaft. The longitudinal movement of the hollow shaft is for the purpose of advancing the ribbon, while the oscillation of the shaft 214 is for the purpose of operating holding jaws to effect grasping of the bent ribbon. At the left hand end of shaft 214 there is a bracket 217 affixed to the shaft by means of integral split arms which are clamped about the shaft by screws 218. The lower end of the bracket, see FIG. 14, is squared to form a key 220 riding longitudinally between key guides 222 and movable oscillatably about the axis of the shaft 214. The key guides are fastened by screws 223 to opposite sides of an oscillatable lever 224, see FIG. 12, journaled on a stub shaft 226 fixed in a journal 228 supported by the casing 110. The lever is oscillated by a link 230 under control of a cam. Thus, as the link oscillates the lever about the shaft 226, the two key guides straddling the bracket 217 will oscillate the bracket and affixed shaft 214 while permitting the shaft and bracket to slide longitudinally of the key guides. The right hand end of the shaft 214 carries a cam 232 adapted to operate a lever and through it a ribbon clamping jaw, as will be described. The shaft 214, while free to rotate in the sleeve, is constrained to move longitudinally therewith by reason of the bracket and cam and through intermediate washers 234 engaging the ends of the sleeve. The sleeve is reciprocated by an arm 236 split at the bottom and suitably clamped to the sleeve by screws 238 and driven longitudinally of the sleeve by a link 240 driven by a cam.

Brazed to the right hand end of sleeve 212, FIG. 12, is a collar 242 to which is fastened a tool-slide guide support 244 as by screws 246. At the back of the support 244, to the right of FIG. 10, is fastened a wear resistant guide rail 248 and cap plate 250 to slidably accommodate a key 252 fastened to a support 254 on the casting 110. This key prevents rotation of the forming head 42 and associated hollow shaft 212 carried by the head. The jaws to grasp the ribbon and advance the ribbon by movement of the head longitudinally of the axis of the sleeve are comprised of a jaw including an insert 256, FIG. 10, and a second jaw with cooperating inserts 258 of shapes similar to the hard ribbon bending inserts 196 and 194 previously described, and their mounting and adjustment are similar to the mounting and adjustment of the ribbon bending inserts. Inserts 258 are shifted by the plate 260 reacting against a spring 262 in a recess in the slide and bearing against an abutment 264 in the slide adjustably positioned by a screw 266 threaded through a plate 268 fastened to a slide guide 270 in turn fastened to the guide support 244, as by screws 271. A cap plate 272 holds the slide 260 in the guide. The slide 260 and the inserts 258 are moved back against the force of spring 262 by a

lever 274 pivoted on a headed pin 276 fixed in the guide support 244 and having a cam follower 278 cooperating with the cam 232. The upper end of the lever, FIG. 10, bears against a shoulder 279 in a side slot of the slide 260 and is effective upon oscillation of the shaft 214 to separate the jaws including the inserts 256 and 258 or to release the slide to enable the inserts to grasp the ribbon. When the ribbon has been clamped by the inserts, the shaft 214, sleeve 212 and feeding head 42 are shifted longitudinally to feed the ribbon to the right, FIG. 12, and then upon release of the jaws, the assembly is retracted to obtain a new bite on the ribbon. Upon feeding of the ribbon to the right, it is fed in between clamping jaws of cutting head 44, see FIGS. 15 to 21, so that the ribbon may be cut off by the cutters 46, 47 and 49.

Head 44 is mounted on frame 102 and includes ribbon clamping elements in the form of a pressure pad 280 and a pair of superimposed plates 282 and 284, see FIG. 16, all hard tipped, with the hard tips on plates 282, 284 forming a V and the hard tip on the pressure pad being correspondingly bevelled to fit the V. The plates 282 and 284 are affixed to a frame block 286 forming part of the head 44 by screws 287 passing through a cap plate 288 and the plates 282 and 284. The block 286 is adjustably slidably mounted on the spacing block 291, see FIG. 17, and held thereto by cap screws 289 threaded into the block 291 and passing through slots in bottom flanges of the block 286. The block 291 is fastened to the frame 102 by screws 293. A bar 290 fast on the spacing block 291 is provided with push-pull screws 292 and 294, FIG. 19, to adjust the frame, the one threaded through the bar and thrusting against the block 286, and the other passing freely through the bar and threaded into the block. Thus the front faces of the plates 282 and 284 may be brought into proper lateral position with reference to the ribbon. The pressure pad 280 is connected through the intermediary of an integral vertical plate 296, FIG. 18, and screws 298 to a slide 300, FIG. 20, in turn connected to a cam driven link 302, FIG. 15. The slide is mounted in a dovetail guide of which the upper part 303, FIG. 20, is integral with the frame block 286 via an integral central web portion 304 and of which the lower part is constituted of a gib 306 held to the central web by screws 308. To the back end of the slide 300, see FIGS. 19 and 21, is secured a hanger 310 by screws 311, see FIG. 19. A spring 312 reacts between a shouldered stud 314, frictionally held in the hanger, and the central web 304 of the frame block. The spring 312 tends to thrust the pressure pad 280 toward the plates 282 and 284 while the link 302 thrusts the pad in the opposite direction and frees the ribbon. The hanger 310 also has an extension carrying an adjusting screw 316, see FIG. 19a, to engage an upstanding bar 318 extending from the frame 102, to limit the separating movement of the pressure pad 280.

Considering FIG. 18, the right hand ends of the hard metal inserts in the plates 282 and 284 are squared off and combine to form a composite shearing edge 46 running backwardly or transversely of the machine a very short distance. Spaced from the edge 46, longitudinally of the machine, is another composite hard metal shearing edge 47 carried by forward prolongations of two superimposed plates 320 and 322, FIGS. 16 and 17, held to an adjustable slide 324 by screws 326 and a plate 328. The slide is adjustable in a slot in the top of the frame block 286 and is held to adjusted position by a push-pull screw arrangement 330 and 332, FIG. 15, mounted in a block 334, FIGS. 15 and 19, held to the frame block 286 by screws 336. Each of the shearing edges 46 and 47 is of composite form because of the difficulty in cutting a V notch in hard alloys.

The edges 46 and 47 are spaced apart the distance of the width of a cooperating shearing knife 49. The shearing knife 49 has, in section, a rectangular portion 340 and a bevelled face 341 in back of the rectangular por-

tion, for a purpose to be described. Its portion 340 moves in between the shearing edges 46 and 47 and blanks out a slug of ribbon which is removed via a conduit 342 having its orifice beneath the shearing edges 46, 47 and 49, and the suction being produced in known fashion by the venturi 343, FIG. 17, supported in the angled block 345 fastened to the frame block 286. The pressure line 344 to the venturi is under cam valve control. The shearing knife 49 is supported by a vertical plate 346 fastened to a second slide 348 by screws 349. The slide 348, FIG. 20, moves in a dovetail guide formed in part by the block 286 and a gib 350 held to the vertical web of the block 286 by recessed screws 352. The slide 348 is operated to bring the knife 49 in between the shearing edges 46 and 47 by a cam operated link 354, FIGS. 15 and 17. The slide is urged toward the left in FIGS. 15, 17 and 21 by a compression spring 356 interposed between a pin 358 in the vertical web 304 and an abutment 360 carried by the slide 348.

Immediately adjacent the cut-off assembly is the transfer head 48 for transporting a cut-off portion of ribbon transversely of the machine to a position where the arms of the dihedral angled ribbon embrace the bared sections of the filament. The mechanism in the head further effects crimping of the angled ribbon about the filament. The head is shown in detail in FIGS. 22 to 31 and includes two jaws 361 and 362, FIGS. 24 and 31, and a plunger 364. The jaws are each composite in character comprising a crimping member 366 and a backup member 368, suitably vertically slidably held to a block 369 in turn fastened to vertically movable top and bottom slides 370 and 372, FIG. 27. The usual push-pull screw adjusting arrangement 373, FIG. 24, is employed passing through a block 374 fastened to the block 369. The two slides 370 and 372 are vertical and are mounted on a vertical base 375, FIG. 29, in turn fastened to a horizontal slide 376 operated by a spring link 377, as will be described. The slide 376, FIG. 30, is mounted in a main block 378 having a dovetail guide for the slide formed in part by a vertical web 380 of the block and in part by a gib 382 fastened to the block. The plunger 364, FIGS. 29 and 31, is L shaped in plan view to enable the short leg of the L to extend along the ridge of the cut ribbon section and support the back of the ribbon. The long leg is slidable in the forward end of companion arms 385, FIGS. 23 and 29, held to the base 375 by suitable screws and is provided with a forward travel limit collar 384, FIG. 29, and against which a spring 386 bears, the other end of the spring surrounding a rounded portion 387 of the long leg, the rounded portion sliding in a guide 388 on the lower gib 408 with the spring abutting the guide. The spring pressure of the plunger in the direction of the jaws 361 and 362 is adjusted to allow thrust of the ribbon into between the plunger and jaws when the ribbon is advanced by the ribbon advancing mechanism previously described, the plunger for this purpose being tapered at its head end in the direction of thrust of the ribbon to permit entry of the ribbon between the plunger and jaws.

The jaw and plunger assembly is transported transversely of the machine by operation of the spring link 377. To accurately position the head in both its retracted positions wherein the ribbon is fed into between the jaws and plunger and its advanced position where the ribbon section is over and underlies the filament ready for crimping about the filament, inclined limit stops 390 and 392, FIG. 25, are adjustably mounted on the block 378. Each of the stops is rendered effectively laterally adjustable with reference to the slide by making it integral with a vertical strap 394 provided with vertical slots 396 through which fastening screws 398 are threaded into the gib 382 and main block 378. By shifting the strap vertically, in effect, the associated inclined stop is shifted laterally. The slide 376, see FIGS. 25 and 29, has tapered faces 400 and 402 alternatively abutting the

stops, only face 400 being visible in FIG. 25, since face 402 is abutting the stop 390. Push-pull screws 403 are threaded through and passing through a screw block 404 fastened to the gib 382. The link 377 is of the well known type wherein springs permit overriding of the driving end of the link in either direction. It is connected at the slide end to the slide through the intermediary of a drive block 405.

As previously described, the upper and lower ribbon holding and crimping tools 361 and 362 are mounted on the vertical guide bar 375, FIG. 27, fixed to the forward end of the slide 376. The guide bar 375 and associated gibs 408, see FIGS. 26, 27 and 29, provide dovetail grooves for the vertical upper and lower tool slides 370 and 372. The two vertical slides are urged apart by a spring 414, FIG. 27, in recesses in both slides, and the slides are moved toward each other by the rollers 415 on the two levers 416 pivoted at 417, FIG. 24, on the gibs 408.

The levers are operated by a stepped cam 418 at the end of a slide 420 operated by a link 422. The slide is mounted in a recess in the web 380, FIG. 30, of the main block 378 and is held to the main block by a face plate 424 suitably secured to the main block. The cam 418 comprises three pairs of steps 426, 428 and 430 of progressively greater height. When the levers are pressed by action of the spring 414 between the vertical slides against the pair of steps 426, the jaws 361 and 362 are separated, as shown in FIG. 31, to permit free entry of the uncut ribbon. When the slide 420 with its stepped cam 418 is moved to position the steps 428 beneath the back ends of the levers, the levers are moved to close the jaws lightly on the upper and lower edges of the bent ribbon to hold the ribbon fairly firmly. The ribbon is so held while the whole jaw assembly is moved to transfer the ribbon toward the filament. During the motion of the transfer device, the just cut end of the ribbon section bears against the hard adjacent bevelled face 341 of the knife 349, see FIG. 15. As a result, the ribbon will be shifted slightly to the right, FIG. 1a, to position the ribbon section with respect to the transfer jaws to leave exposed ends of the ribbons for subsequently being grasped by other holding jaws on a welder. Cams which operate the links 377 and 422 are so designed that during the transfer of the ribbon section to a position embracing the filament, steps 428 of the cam slide will be in position between the lever ends. After the ribbon has been transferred to embrace the filament, the cam slide 420 will be operated to move the cam surfaces 430 between the arms 416, to close the tools further on the ribbon, thereby causing the two dihedral arms of the ribbon to come into contact with each other and the filament to be rigidly held in the bite of the ribbon section. The ribbon section projects slightly beyond both the sides of the jaws, thereby leaving the ends of the section with flared sides to enable, in an assembled electron tube, flexing of the filament about its tab without rupture of the filament.

After the transfer head has crimped the ribbon section about the filament and brought the leaves of the section forming the arms of the dihedral angle together, the leaves are welded together and to the filament. The welding mechanism is illustrated in FIGS. 32 to 42. It comprises two main parts mounted on a bracket 450 fixed with relation to the frame 102. Fixed on this bracket is an upright mounting block 452, see FIGS. 33 and 34 mounting a pair of upper and lower holding tools 454 and 456 for holding the ribbon section after the transfer jaws have moved the ribbon section over the filament and crimped the section and prior to gripping of the section by welding electrodes, and the bracket 450 provides two vertically aligned journals 458 and 460 accommodating two slidable rods 462 fastened to a movable frame 464 of which the electrode pivot supporting arms 456 form a part. The frame 464 also has a combined mo-

tor cylinder and shelf 467, see FIG. 35, which will be described later on. Thus the welding electrodes are shiftable to a position over and under the ribbon section after the ribbon section transfer jaws have been retracted and while the ribbon section is still held by the holding jaws 454 and 456. The holding jaws are released after the welding electrodes have engaged the ribbon section. The top holding jaw, see FIG. 33, is fastened by a cap screw 468 to an adjusting block 470 which has push-pull screws 472 to adjust the jaw longitudinally of the machine. The free end of the jaw comprises two tines 474, see FIG. 40, each provided with a long hard alloy finger 476 to engage the ribbon section at points straddling the upper transfer jaw on head 48. The lower holder 456 has similar fingers and inserts which extend upwardly to engage the under face of the ribbon section and straddle the lower transfer jaw. It is between these inserts that welder electrodes enter, after the transfer jaws have receded. In FIG. 33 the upper thin welding electrodes are indicated as 478 and 480 and the bottom single wide electrode is indicated as 482. The lower holder, like the upper one, is mounted on an adjusting block 490, see FIG. 41. The adjusting block 470 is L-shaped and mounted on a vertically movable slide 488 while the adjusting block 490 is L-shaped and mounted on a vertically movable slide 492, see FIGS. 32, 36 and 37. The slide 488, see FIG. 36, is provided with a roller 494 while the slide 492 is provided with a roller 496. These rollers on the slides are shifted to vertically move the holding jaws apart by a stepped thrust piston rod 498, see FIG. 37, having a thin part 500 at the end to enable the holding jaws to close on the ribbon section and a stepped wider part 502 operative on thrust of the rod to vertically separate the jaws. The rod has a flat section 504 riding in a correspondingly shaped portion of the upright block 452 to prevent piston rod rotation. At the forward end of the rod is the piston 506 in a piston chamber closed off by a ported cap plate 508 through which fluid pressure is supplied under control of a cam movable with the cams of the machine which control the motions of the various heads, etc. The slides 488 and 492 ride in vertical dovetail grooves formed in part by the block 452 and in part by gibbs 510 fastened to the block. To hold the rollers against the stepped end of the piston rod, the roller 494 rotates on a pin 512 whose outer end extends beyond the face of the slide; a tension spring 514 is hooked into the pin and into a plate 516 fastened to the bracket 450. The slide roller 496 is pressed against the steps on the piston rod by a compression spring 518 housed in recesses in the slide 492 and in the bracket 450. Fastened to the block 452, see FIGS. 32 and 36, is a stop plate 520 through which a limit stop screw 522 is threaded to limit the ribbon section approach movement of the lower holding jaw and its arm 490. A lock plate 524 overlies the stop plate 520 through which the limit screw 522 is threaded and through which a second headed screw 526, FIG. 32, is passed freely and threaded into the plate 520. As a result of this arrangement the stop screw 522 may be finely adjusted and fixedly held to its adjustment by operation of the screw 526 and plate 524. A similar arrangement is provided for the upper tool holding slide 488 but in this case the plate 525 corresponding to plate 520 is secured to the slide 488 and the stop screw 527 corresponding to screw 522, engages the top of plate 520.

While the holding jaw assembly is mounted on the fixed bracket 450, the electrodes and their moving mechanism are mounted on the movable frame 464. The frame 464 is shifted toward the ribbon section and filament assembly by cam operated link 530, see FIGS. 32, 33 and 34, connected to a pin 532 in a lateral projection 534 of the frame 464. Thus as the link is reciprocated, the rods 462 will slide in the journals 460 and the entire electrode structure will be shifted.

The pivot supporting arms 466 of the shiftable frame

support a pivot pin 536 on which are mounted roller bearings 538, FIG. 38. The central roller bearings pivotally support a triple armed lower electrode supporting lever 540, see FIG. 35, while the outer sets of bearings pivot 5 upper electrode, L-shaped, supporting levers 542 and 544, see FIGS. 35 and 38. To the lower face of the lower lever 540, is attached a bottom electrode retainer 546 insulated from the lever 540 by sheet insulation 548, FIG. 38. The screws which hold the electrode retainer to the lever are also suitably insulated by insulating bushings and insulating washers as will be explained in connection with the top electrodes. An electrode lead-in wire from a welding transformer is connected to one of these screws, as screw 550, FIG. 35. The lower electrode 482 is held adjustably in place in the retainer 546 by a suitable clamping plate 552, as shown in FIGS. 33 and 42. The lower electrode is of a width to substantially bridge the entire tightly folded over portion of the ribbon section and is wide enough to directly underlie the points of the upper electrodes. It is narrow enough to lie, without contact, between the hard metal inserts of the lower holding jaw. Likewise, the upper electrodes 478 and 480 are out of contact with the upper holding jaw inserts. Of course, the welding current is not shot through the electrodes until after the transfer jaws have moved away from the ribbon section and then it is shot in succession through the two upper electrodes and the common bottom electrode.

Each of the upper electrode support levers 542 and 544, see FIGS. 32, 35 and 38, carries a guide arm, as arm 554, the same being insulated from its lever by sheet insulation 556. Each of the arms is held to its lever by screws 558 passing through insulating bushings 560 and insulating washers 562 and threaded into the associated lever. Separate lead-in wires from the welding transformer are fastened in between an insulating washer and the arm 554 therebeneath. Each of these lead-in wires is in series with a switch under cam control.

The forward ends of the arms are shaped to hold the electrodes 478 or 480, see FIG. 32, between a hooked end of retainer 564 and a clamping plate 566 secured thereto, as by screw 568. The electrodes 478 and 480 are adjustable toward each other by slide and push-pull screws, in the same manner as the holding jaws are adjusted.

The upper electrodes are separated from the bottom electrode by the stepped end of a vertical piston rod 570, see FIG. 35, provided with a flat section 571 cooperating with a guide 572 on the bracket to prevent rotation of the rod. The lower end of the rod is connected to a piston 573 in a chamber in the movable bracket 464, the chamber being closed off by a ported cap plate 574 whose port is connected to a fluid pressure line, the pressure being under control of a cam. A spring 575 urges the piston to its lowermost position. When the piston rod is fully projected upward, rollers 576, one each on the lower ends of electrode support levers 542 and 544, bear against the wide step 578 of the rod. At this time a roller 580 on the bottom electrode lever is also resting against its step 582. It will be noticed the step 582 is shorter than the step 578 so that as the piston rod descends, the lower electrode support lever 540 will be released to allow the projection 584 of the lever to engage an adjustable stop 586 on the frame 464 prior to the release of electrode supporting levers 542 and 544.

This is to properly position the lower electrode 482 against the ribbon section prior to descent of the electrodes 478 and 480. The electrode retainer 546 and the lever 540 are urged counterclockwise in FIG. 35 and against the stop 586 by the action of a stiff spring 588 supported in a barrel 590 fastened in the shelf 467 of the movable frame by a screw 591 and urging an insulating pad 592 against the under side of the retainer 546. Each of the levers 542 and 544 is urged clockwise about its bearings to bring the electrodes 478 and 480 atop the

ribbon section, see FIG. 33, by a light spring 594, compared to spring 588, stretched between an electrode arm and a swivel cap 596 mounted on an adjustable screw 598 mounted in the shelf 467. The spring 588 is greater in strength than the combined strength of the two springs 594 so that the lower electrode will not be moved downward when the upper electrodes press against the ribbon section. A dowel pin 599 riding in a slot in the barrel 590 limits the motion of the insulating pad.

After the tab material has been welded onto the bared sections of the filament, it is pulled by mechanism to be described to a suitable position between cutting knives of a head 60 to cut the tabbed filament into separate filaments, each with a tab at each end, as shown in FIG. 2c. The cutting knives and associated mechanism is illustrated in FIGS. 43 to 48 and is mounted on a bracket 600 spaced from the right hand end of the frame 102 as viewed in FIG. 2a by upper and lower gauge or spacer blocks 601 and 602, interposed between the bracket 600 and the end of the frame 102. The thickness of the blocks will vary in accordance with the desired spacing desired between the cutting knives and the welder. The bracket 600 is slidably mounted on a pair of horizontally aligned shafts 604, the free ends of the shafts passing through openings in the end wall of frame 102 and secured against lateral shift by set screws 606, FIG. 46, and backing up lock screws 608. To facilitate exchange of gauge blocks, springs 610 are seated in the bracket 600 and bear against the frame to separate the bracket and frame as soon as the screws 611 passing freely through the bracket and threaded into frame 102 are backed off. Preferably the blocks have recesses formed upwardly from the lower faces of the blocks to seat on the screws 611 to enable the blocks to be easily slipped up and laterally out from between the bracket and frame once the springs 610 have pushed the bracket away from the frame, the upper gauge block being of an extent to lie between the shafts 604. Fastened on the bracket 600, as by screws 613, is the cutter head frame 612, and adjustable on this head frame, transversely of the machine is the cutter head block 614, FIGS. 45, 47 and 48. Also fastened to the head frame as by screws 615, is a standard 618, supporting a plate 620 with a polished upper surface, the plate substantially bridging the space between the welder and the head 60 and supporting the tabbed filament in its transfer from the welder to the cutter. On the head there are holding jaws provided to grasp the tabbed filament while the cutting knives are operating.

In FIG. 45, toward the right of the figure, there is shown an upper holding jaw retainer 622 and a companion low holding jaw retainer 624 normally held apart by a compression spring 626 seated in opposed recesses in the retainers. The retainers are fastened by means of screws 628 to upper and lower reciprocatable vertical guides or slides 629 and 630 each riding in a dovetail groove formed in part by a gib 631 fastened to the block 614 and a companion shaped integral portion of the block. Carried by the jaw retainer 622 and adjustable thereon in a fixed relation thereto is a tool holder 632. To adjust and fix the retainer, the block 622 has fastened thereto by screws 633 an adjusting block 634 in which, see FIG. 46, there is threaded a screw 635 pushing against the retainer 632 and a second headed screw 636 passing freely through the block 634 and threaded into the retainer 632. Thus the holder 632 may be finely adjusted and held to adjusted position by screws 637 passing through a plate 638 and the retainer 632 and into the block 622. The slide 632 has a tapering portion 639 directed toward the line of longitudinal movement of the tabbed filament and at its free end is provided with a hard squared off insert 640 to engage the top of the tabbed filament when the tool retainer is depressed. Similarly, the lower tool holder is

arranged to have its tool 641 adjustable toward and from the plane of the lower face of the tabbed filament.

To operate the tool holding jaw retainers 622 and 624 against the action of spring 626, there is provided upper and lower levers 642 and 644, FIG. 45, each pivotally mounted on a pivot pin 646 mounted in the associated gib 631, and having a front roller 647 bearing against an associated jaw retainer 622 or 624 and a rear cam follower 648 operated by a stepped cam bar 650 connected to a link 652, in turn operated by a cam. The cam bar, see FIG. 47, operates in a recess in the block 614 and is held in the recess by a cover plate 654. When the bar is thrust forward toward the holding jaws, see FIG. 45, the jaws will close on the ribbon section near an end thereof, the mid portion of the ribbon section lying between cutting knives. When the cam bar is retracted, the holding jaws will open under influence of the spring 626. A polished plate 656 fastened to the block 614 provides guidance of the ribbon section and filament assembly to the holding and cutting station. A pipe 658 with ports 660 is provided to blow dust and dirt from off the plate, under cam and valve control.

The cutting knives themselves are arranged diagonally of the machine to provide a diagonal cut to near the center portion of the ribbon section. This is to provide pointed ends on the consequentially formed filament tabs so as to enable them to be easily passed through slots in micas where the tabbed filament is assembled with spacing micas in a tube structure.

The knives are shown in FIGS. 44 and 46 as an upper knife 662 and a lower knife 664. FIG. 49 shows a very much enlarged view of the association of the lower knife and the ribboned filament, the cutting plane of the knives being indicated along the line 666. The upper knife 662, see FIGS. 44 and 46, is mounted at the lower edge of a horizontally shiftable slide 668 riding in a horizontal recess in the forward end of a cutter slide retainer 670 to which is fastened an adjusting block 672, as by screws 674. Push and pull screws 676 and 678, arranged similar to those already described in connection with other slides, effect adjustment of the slide 668. The slide is fastened to the retainer by screws 680 and a plate 682 as will be understood by referring to previously described similar constructions. The lateral adjustment of the slide is to provide for accurate meeting of the knives at the cutting plane indicated by the line 666 in FIG. 49. The retainer 670, FIG. 44, is fixed by screws 684 to a vertical upper slide 686 dovetailed in the head block 614 and the associated gib 688. Mounted in the gib is a pivot 690 supporting an upper operating lever 692 whose forward end engages the upper face of the retainer to drive it downwardly and whose rear end is operated by a cutter cam bar 694 driven by a link 696, in turn driven by a confined cam. The cam bar 694, FIG. 47, lies in a horizontal recess in head block 614 and is closed off by a cover plate 698. The bottom cutter knife 664, FIG. 44, is mounted at the top of a vertical slide 700 vertically adjustable in a vertical recess in the lower cutter slide retainer 702 by means of push pull screws 704, 706, locking plate 710 and plate screws 708, as will be understood by reference to previous similar arrangements. The retainer 702 is mounted on a lower vertical dovetailed slide 711, FIG. 48, similar to the upper slide 686 by screws 712, and the retainer is operated by a lower operating lever 714 in a manner similar to the operation of the upper retainer. However, the cams on the end of the cam bar 694 are so positioned that upon retraction of the bar to the right, as viewed in FIG. 44, the bottom lever will be operated first to bring the lower cutting knife to the plane of the lower face of the ribboned section. This is possible because of the vertical adjustment of the cutting knife afforded by the push pull screws 704 and 706. The cutting slide retainers 670 and 702 are separated by action of a compression spring 716 whose ends lie in opposed recesses in the retainers. The spring is operative on advance of

the cam bar to the left in FIG. 44 to separate the retainer and the knives.

In so far as the forming of the tabbed filament is concerned, the operation has been completed. However, to avoid entanglement of filaments at the tab cutter, it is necessary to remove the fine tabbed filament from the area of the cutter. Furthermore, obviously, it is necessary to draw a new ribbon sectioned filament into proper position for being cut. The drawing of the filament and ribbon section assembly is shown in detail in FIGS. 50 to 54 and is effected by a pair of pulling jaws 720 and 722 pivoted together on a pin 724 supported at the ends of a fork 726 non rotatably mounted on a barrel 728 by the aid of a key 730. Each jaw is provided with a hard tip, the jaws being normally held apart by a compression spring 732 whose ends are seated in recesses in the jaws. The jaws are urged to closed position by longitudinal movement of a pointed piston rod 734 thrusting against rollers 736 and 737 axled at the rear ends of the pulling jaws. The piston rod is rigid with a piston 738 behind which fluid pressure is admitted via a port 740 in a journal housing 742 mounted on a frame 743 longitudinally adjustably mounted on the top of a cam housing to be described. The port 740 leads via additional communicating passageways to behind the piston. Air under pressure is admitted under control of a solenoid operated valve in casing 744, the solenoid of the valve being under control of a cam operated switch. The rod is retracted by a compression spring 746 surrounding the rod and reacting between a bushing 748 in the barrel and the piston 738. The valve to close the pulling jaws is operated to close the pulling jaws after they have engaged a leading end of a tabbed filament, prior to release of the filament by the holding jaws of the cutter head, and after the cutter knives have separated. The valve is operated to release the air pressure after the pulling jaws have laid a tabbed filament over a transfer drum, as will be described, and after the pulling jaws have been withdrawn from the cutting knives. The pulling jaws are advanced toward the holding jaws under cam control. The barrel 728 is integral with a shaft 750 whose right hand end, FIG. 51, rides in a smooth liner 752 in a bearing housing 754 forming part of the frame 743. The free end of housing 754 is closed off by a cap plate 756 to provide a closed chamber behind the shaft into which air at constant pressure is supplied by a pipe 757 to advance the jaws toward the cutter head. To control the advance of the jaws, the shaft has clamped thereto a two part collar 758, 759. The portion 759 supports a cam follower roller 760 bearing against a face cam 762 mounted on a drive shaft 764 geared to the cam shaft of the machine. The throw of the cam is indicated by the dotted line position of roller 760. A pair of aligning rollers 768 and 770, see FIGS. 52 and 53, mounted on the collar portion 758, straddle a track 772 secured to the housings 742 and 754 to prevent the shaft and attached jaws from rotating about the axis of the shaft.

To transport a tabbed filament from the pulling jaws to a receiver beneath the jaws, there is provided a transfer mechanism shown in FIGS. 55 to 60. In general it comprises an indexable transfer turret 780 fixedly mounted on a horizontal hollow shaft 782, see FIG. 58, indexable in bearings in a spider housing 783. The turret is provided with four radially shiftable vacuum heads 784, the transfer turret being indexable through two 45° steps for receipt of each filament. As viewed in FIG. 56 the turret comprises a scalloped plate 786 provided with seats on which are fastened four pairs of gibs 788 forming between each pair and the plate a dovetailed slideway for a slide 790. To the outer end of each slide is fastened by a screw 793, FIG. 58, a mounting block 792 in which is fastened, as by a screw 794, the hollow stem of the vacuum head 784 provided with a longitudinal V shaped notch 798 to receive the tabbed filament and in this notch are ports 800 communicating via a manifold with the

hollow in the stem. A chamber 802 in the mounting block 792 communicates via a pipe 804, FIG. 56, with a passage 806 in the plate 786 displaced 45° from its associated vacuum head. The port opens to the side face of the plate and there communicates with a long arcuate suction passage 808 in an oscillatable plate 810 mounted in housing 811, FIG. 59, the housing 811 being oscillatably mounted on the spider housing 783. The housing 783 is secured to a cam housing 812 fixed with relation to frame 102 and on which the filament and tab assembly feed mechanism is mounted. The suction passage is connected by a pipe 813 to a suitable suction pump via a cam controlled valve. To maintain the vacuum control plate against the ported side of the turret plate, the housing 811 is recessed and provided with four springs 814 spaced 90° around the housing and bearing against a friction plate 816 oscillated with the housing by reason of a dowel pin connection 818 and reacting against a shoudered part 820 on the housing 783. As the shaft 782 and transfer plate 786 are indexed around with respect to the housing 783 by mechanism to be described, the approaching top head 784 will not be subjected to suction until its associated 45° displaced port 806 reaches the long arcuate recess 808. Suction is controlled by oscillation of housing 811 and plate 810 through link 822, FIG. 55. As the plate 780 is indexed clockwise from the position as viewed in FIGS. 56 and 59 the suction will be maintained on the said head until it reaches its bottommost position. At this time suction will still be maintained on because the port close to the end of the elongated recess is still in communication with the port 806. However, after the head has reached its lowermost position, the vacuum control housing 811 is oscillated by the cam driven link 822 from where the arcuate port's terminations are shown in dotted lines in FIG. 59 to the full line positions thereof. As a result, the suction to the bottommost head is cut off and enough leakage develops in the ports 800 about the filament to allow the filament to drop into any convenient receptacle, as receptacle 68 in the form of a tray 824 having an end wall 825. A second short arcuate passage 826 is provided in the front of the plate 810 through which air is blown via a conduit 828 and slot 830 in the back of the plate to blow out any dirt that may have lodged in the vacuum head passages as the upgoing heads sweep by.

The means for indexing the hollow shaft comprises a spider 832, FIG. 57, having eight equally spaced rollers 834 mounted thereon and a cooperating double cross over track cam 836, FIG. 58, on a constantly driven shaft 840. A development of the cross over cam is shown in FIG. 61. Each revolution of the drum will advance the spider through two 45° steps with intermediate dwells.

After initiation of index of the spider through its first 45° step and prior to the completion of the second index movement of 45°, the tabbed filament feed assembly jaws move to the left, FIG. 58, to grasp a tab on a tabbed filament and transport the same to the right. After a proper length of the tabbed filament has been pulled between the cutting knives 662 and 664 and just as the cutting knives are effective to cut through the tab section and filament, the tension on the filament is momentarily released by a slight forward motion of filament feed mechanism, see FIG. 50. The filament, when severed from the string and subsequently transported still further to the right by the jaws, will probably be bowed because of the weight of the unsupported tabbed end of the filament, at the end of the second 45° index of the plate it is necessary for the top suction head to come under the filament to then rise and support the entire filament. It is for this purpose that the heads are supported on slides, and associated slide moving mechanism is provided. The slides are normally urged to a head retracted position by each being provided with a spring 842, see FIGS. 58 and 60, positioned in a recess in the slide and reacting against a stop pin 844 set in the plate 786. The lower end of

each slide is provided with a cam follower roller 846 riding around a cam 848, see FIG. 56, provided with an elongated hump 850 and a short bump 852 which are in the positions shown in FIG. 56 when the pulling jaws are at the extreme right. The cam 848 is mounted on an oscillatable shaft 854 in bearings in the hollow shaft 782, the oscillatable shaft having a crank arm 856 affixed to one end thereof. A cam operated pitman 853 is connected to the arm to oscillate the shaft and cam 848.

When the transfer plate starts to index so does the 10 cam 848 and in the same direction so that the cam follower roller 846 continues to ride on the elongated bump, thus clearing the tabbed filament out of the now opened pulling jaws 720, 722 without drag or bend. At the start, the cam 848 is in position with the bump 852 below and 15 to the left of the axis of shaft 782 and the lowermost head 784 is retracted in the spider and above a tray so that the lower suction head may clear the end wall of a tray in the arcuate index movement of the head. During about the first 35° of movement of the head, the cam 848, under control of the cam driving the link 858, moves 20 around with the transfer plate. Then, the cam 848 is oscillated counterclockwise to bring the cam back to the position shown in FIG. 56. At this time however, due to the angular position of the transfer plate, all the suction 25 heads are retracted. When the transfer plate reaches a position 90° displaced from the start, the suction heads are still retracted because the rollers 846 are on low points of the cam. At this time, the filament transfer devices will have completed pulling a severed tabbed filament over the top suction head. A little later the cam 848 will be oscillated counterclockwise to advance both 30 uppermost and lowermost heads, the uppermost head then by suction engaging and holding the filament and the lowermost head having its suction cut off to allow the lowermost filament to fall a short distance into the tray. Next the cam 848 is shifted clockwise sufficient to allow 35 the lower head to be retracted. But, because of the elongated bump 850 on the cam, the upper head is held in the thrust upward position. This brings the parts back to 40 the start for a new index operation.

The various cams for driving the parts and controlling the valves for the various fluid motors and the switches for the welding electrodes have not been referred to in detail. Their relative position and timing is clear however from FIGS. 62, 63 and 63a. The contours of the cams would correspond with the rise and fall of the lines in the timing chart. In FIG. 62 there is diagrammed a motor driving intergeared shafting mounting various cams, which in turn through conventional bell crank levers 860 drive the various links referred to heretofore. The cams marked C are confined cams, i.e., cams whose side faces contain recessed tracks in which a cam follower roller of a bell crank rides, while the cams E indicate cams having peripheral or edge surfaces on which the bell 45 crank follower roller ride. The parts marked V or S indicate respectively air valves and switches and the valve or switch served is indicated by the character applied thereto.

What is claimed is:

1. A filament tabbing machine comprising a ribbon centering device, a ribbon former, a ribbon feed device and a ribbon cutting device arranged in the order named along a longitudinal axis of the machine, said ribbon centering device having means for centering the ribbon both vertically and laterally with respect to the ribbon former, and said ribbon former having a reciprocable element and means to reciprocate the element, and means for longitudinally reciprocating the ribbon feed device to pull a ribbon through the ribbon centering device and the ribbon former and to thrust the ribbon into the ribbon cutting device.

2. A filament tabbing machine comprising a ribbon centering device, a ribbon former, a ribbon feed device and a ribbon cutting device arranged in the order named

75

along a longitudinal axis of the machine, means for longitudinally reciprocating the ribbon feed device to pull a ribbon through the ribbon centering device and the ribbon former and to thrust the ribbon into the ribbon cutting device, ribbon transfer jaws arranged next to the cutting device between which the ribbon is thrust by operation of the feed device, means adapted to guide a filament so as to move in a path laterally of the path of travel of the ribbon and parallel thereto, mechanism to move the transfer jaws transversely of the machine and to move the jaws toward each other to crimp the formed cut off ribbon section carried by the jaws about the filament, ribbon holding jaws straddling the transfer jaws in the position where the formed and crimped ribbon section overlies and underlies the filament, and welding electrodes positionable to engage the ribbon section between the holding jaws, when the transfer jaws have been retracted, means to shift the electrodes into and out of said position, and means to control the application of welding current to said electrodes when in said position.

3. A filament tabbing machine comprising a ribbon centering device, a ribbon former, a ribbon feed device and a ribbon cutting device arranged in the order named along a longitudinal axis of the machine, means for longitudinally reciprocating the ribbon feed device to pull a ribbon through the ribbon centering device and the ribbon former and to thrust the ribbon into the ribbon cutting device, ribbon transfer jaws arranged next to the cutting device between which the ribbon is thrust by operation of the feed device, means adapted to guide a filament so as to move in a path laterally of the path of travel of the ribbon and parallel thereto, mechanism to move the transfer jaws transversely of the machine and to move the jaws toward each other to crimp the formed cut off ribbon section carried by the jaws about the filament, ribbon holding jaws straddling the transfer jaws in the position where the formed and crimped ribbon section overlies and underlies the filament, and welding electrodes positionable to engage the ribbon section between the holding jaws, when the transfer jaws have been retracted, means to shift the electrodes into and out of said position, means to control the application of welding current to said electrodes when in said position, a cutter for the ribboned filament in line with said filament to cut through the ribbon section and filament to make a tab on the filament and beyond the transfer jaws, pulling jaws in line with the filament and operative longitudinally of the machine and mechanism for operating the jaws to move them toward the cutter to grasp the end of a just cut tab and to pull the succeeding ribbon sections and filament through the cutter.

4. A filament tabbing machine comprising a ribbon centering device, a ribbon former, a ribbon feed device and a ribbon cutting device arranged in the order named along a longitudinal axis of the machine, means for longitudinally reciprocating the ribbon feed device to pull the ribbon through the ribbon centering device and the ribbon former and to thrust a ribbon into the ribbon cutting device, ribbon transfer jaws arranged next to the cutting device between which the ribbon is thrust by operation of the feed device, means adapted to guide a filament so as to move in a path laterally of the path of travel of the ribbon and parallel thereto, mechanism to move the transfer jaws transversely of the machine and to move the jaws toward each other to crimp the formed cut off ribbon section carried by the jaws about the filament, ribbon holding jaws straddling the transfer jaws in the position where the formed and crimped ribbon section overlies and underlies the filament, and welding electrodes positionable to engage the ribbon section between the holding jaws, when the transfer jaws have been retracted, means to shift the electrodes into and out of said position, means to control the application of welding current to said electrodes when in said position, a cutter for the ribboned filament in line with said filament to

cut through the ribbon section and filament to make a tab on the filament, pulling jaws for grasping and pulling longitudinally of the machine a just cut tab and the following string of filaments with welded on ribbon sections, a tabbed filament transfer device adjacent the cutter, and having tabbed filament receiving portions positionable beneath the path of movement of the pulling jaws, means for operating the pulling jaws, and means for operating the tabbed filament transfer device.

5. Mechanism for deforming a flat ribbon into a ribbon V-shaped in transverse cross section, said mechanism including in the order named, a ribbon centering device, a ribbon deformer and a ribbon puller, the last pulling the ribbon through the centering device and the deformer, said deforming device including a jaw having a V-shaped groove extending parallel to the length of the ribbon and a second jaw with a V-shaped apex cooperated with the grooved jaw to engage and bend the ribbon about a line running longitudinally of the ribbon and said centering device including mechanism to position the ribbon both laterally and vertically with respect to the forming jaws, said centering mechanism comprising a pair of horizontal blades adjustable to the thickness of the ribbon and adjustable laterally with respect to the vertical plane of the ribbon, a plate support block, two vertical plates slidable in the block, spring means urging the plates to move them equal amounts in opposite directions, said plates having portions to engage the upper and lower edges of the ribbon to center the ribbon with respect to the plates, and means to shift the block vertically to vertically align the ribbon held by the plates with respect to the forming jaws.

6. Mechanism for deforming a flat ribbon into a ribbon V-shaped in transverse cross section, said mechanism including, in the order named, a ribbon centering device, a ribbon deformer and a ribbon puller, the last pulling the ribbon through the centering device and the deformer, said deforming device including a jaw having a V-shaped groove extending parallel to the length of ribbon and a second jaw with a V-shaped apex cooperative with the grooved jaw to engage and bend the ribbon about a line running longitudinally of the ribbon, and said centering device including a vertically adjustable block, two plates vertically slidable in said block, means at the upper edges of the plates to engage respectively the upper and lower edges of the ribbon, means coupling the plates for conjoint movement in opposite directions, and biasing means urging the plates to move in a direction for ribbon engagement.

7. The subject matter of claim 6 together with manually operable means to move the plates to release the ribbon.

8. In a filament tabbing machine, mechanism for guiding a ribbon on edge to a centering device, a ribbon forming mechanism receiving the ribbon from the centering device, a ribbon pulling device beyond the forming device for pulling the ribbon through both the centering device and the forming mechanism, said centering device comprising a front and back blade engageable with the vertical faces of the ribbon and a pair of plates with opposed ribbon edge engaging elements to engage the top and bottom edges of the ribbon, yielding means urging the plates in opposite directions and the ribbon edge engaging elements toward each other, a block slidably mounting the plates, and means for adjusting the block vertically to align the ribbon with the ribbon forming mechanism.

9. In a filament tabbing machine, mechanism for centering, forming and feeding a ribbon comprising a journal supporting a block, said block carrying a horizontal blade and said journal also supporting a second block, said second block carrying a horizontal blade opposite said first horizontal blade, said journal also supporting vertical slides to laterally and vertically center a ribbon pulled past the block, mechanism operative in the block carried by the first block and journal to form the ribbon by bending the same along a line longitudinal of its length, said

feeding mechanism including a slide guide, a jaw carried by a horizontal slide movable in the guide, a sleeve longitudinally slideable in said journal carrying said jaws, means to restrain the sleeve from rotation with respect to said first block, means to reciprocate said sleeve to feed the ribbon longitudinally, an oscillatable shaft in said sleeve movable longitudinally therewith, means to oscillate said shaft and a lever driven by said shaft engaging said horizontal slide for shifting the same to cause the jaws to release the ribbon and means acting on the horizontal slide to cause it to move a jaw toward the companion jaw to engage the ribbon.

10. Mechanism for pulling a ribbon past a ribbon forming mechanism having ribbon forming jaws extending longitudinally thereof, said mechanism comprising a sleeve journaled in said forming mechanism and extending parallel to the longitudinal dimension of said jaws and extending therebeyond in opposite directions, ribbon gripping jaws on one end of said sleeve, sleeve driving means connected near the other end of the sleeve to drive the sleeve longitudinally, an oscillatable shaft within the sleeve and movable longitudinally therewith, means operative on a ribbon gripping jaw to move the same, said means including a part operative in response to oscillation of said shaft, and means to oscillate the shaft including a bracket secured to the shaft, a horizontal guide means cooperating with the bracket to constrain it to move along the guide means, an arm oscillatable about the axis of the shaft supporting the guide means, and drive means to oscillate the arm.

11. In mechanism for feeding and deforming a ribbon and cutting off a section of the deformed ribbon, a ribbon deforming mechanism comprising jaws to give a V formation to the ribbon longitudinally along its length, a centering device in advance of the deforming mechanism to position the ribbon with respect to the deforming mechanism, a pulling mechanism to pull the ribbon through the centering device and deforming mechanism, a combined ribbon holder and ribbon cutter adjacent the deforming mechanism, said holder and cutter having jaws to receive the ribbon thrust therebetween by pulling action of the pulling mechanism on the ribbon, said combined holder and cutter comprising a frame block supporting two horizontally movable slides, a ribbon clamping jaw fixed on the block, a second and cooperating clamping jaw fixed to one of said slides, a pair of cutters spaced longitudinally of the ribbon fixed with reference to the block, a cooperating cutter mounted on the second slide to pass in between the first relatively fixed cutters to cut out a slug from the ribbon to form a ribbon section, and means to operate the two slides.

12. In a filament tabbing machine, mechanism for deforming a ribbon by bending the same about a longitudinal axis of the ribbon into transverse section V formation, mechanism for grasping the bent ribbon and cutting off a section of the ribbon, a head for transferring the bent section with its integral leaves to a location displaced laterally of the length of uncut ribbon, feed mechanism for moving the ribbon through the deforming and cutting mechanisms and pushing the ribbon into the transfer head, said transfer head including a pair of ribbon grasping jaws, means for feeding a filament along a path parallel to the path of movement of the ribbon through the deforming and cutting mechanisms and the head and on a level with the ribbon path, a slide and driving means therefor, connected with the head to move the bent cut off ribbon section to a position where its leaves overlie and underlie the filament, ribbon grasping and crimping jaws mounted in said head, a second slide, a cam on said second slide for operating said jaws to first lightly grasp the ribbon as it is inserted into the head, then grasp the cut off ribbon section more firmly for transportation to the filament and finally to crimp the ribbon section tightly about the filament, and means for operating said last slide.

13. The structure of claim 12 wherein the cutting mech-

anism has a knife which flares outwardly in the direction of transfer movement of the head toward the filament and in the path of movement of the ribbon section toward the filament as it is more firmly grasped by the jaws whereby the ribbon section will be shifted laterally to protrude from both sides of the jaws.

14. In a filament tabbing machine, mechanism for cutting off a ribbon section from a long length of ribbon which has been deformed by bending the length of ribbon into V formation in transverse section, and along a longitudinal axis of the ribbon, means for feeding a filament along a path parallel to the longitudinal length of the ribbon, a transfer head for grasping a cut off ribbon section and transferring it to embrace the filament, the cutting mechanism including a flaring portion extending from the cutting mechanism toward the path of the filament and the flaring portion being in the path of movement to be engaged by the ribbon section as it is transported to cause both ends of the ribbon section to be protruding from the head, a pair of holding jaws above and below the filament, each holding jaw having fingers adapted to straddle the transfer head when it is crimping the ribbon section about the filament and adapted to hold the ends of the crimped ribbon section against movement while the transfer head is retracted, and upper and lower welding electrodes mounted on a shiftable carriage shiftable to cause the electrodes to overlie and underlie the ribbon section, after the transfer head has been retracted, means to shift the carriage, means to move the electrodes toward the ribbon section and control means for applying welding current to the electrodes.

15. The structure of claim 14 wherein the electrode moving means includes springs for moving the electrodes toward the ribbon section, movable supports for the electrodes, a stop in the path of movement of the lower electrode support for limiting the upward movement of the electrode to the lower face of the crimped ribbon section and a cam bar to control the approach movement of the electrodes toward each other, said cam bar being formed to enable the lower electrode to move to its stopped position prior to the downward movement of an upper electrode to ribbon section contact.

16. In a filament tabbing mechanism, ribbon deforming mechanism to deform a flat ribbon to a ribbon which, in section transverse to its longitudinal axis, is V shaped, cutting mechanism in the path of the ribbon for cutting off a section thereof, a transfer and ribbon crimping head movable in a path transverse to the path of movement of the ribbon, means for moving a ribbon through the deforming mechanism and through the cutter head and thrusting the ribbon into the transfer and crimping head, a welder in the transverse path of movement of the head, means for moving it in a path transverse to the path of movement of the ribbon, a filament pulling mechanism for pulling a filament movable in a path parallel to the path of movement of the ribbon, a holding mechanism for engaging a ribbon section crimped on the filament, said holding mechanism including holding jaws above and below the filament, and means for operating the several mechanisms and including means for shifting the head to bring a ribbon section about the filament and to crimp the same thereon and to retract the head, means to bring the holding jaws to hold the ribbon prior to release thereof by the head and while the welder is moving over and engaging the ribbon section and welding the ribbon section onto the filament, means to operate the welder, and means for cutting off a section of the filament through the ribbon section to produce a tabbed filament.

17. In a filament tabbing machine, means for feeding a ribbon longitudinally of itself, means for feeding a filament in a parallel path spaced laterally of the ribbon path, ribbon deforming and ribbon cutting mechanisms and a ribbon section transporting head arranged along the path of ribbon feed to deform a flat ribbon into one with V shaped cross section transversely of the ribbon, to cut

5 off a section of the ribbon and to transport it transversely of the ribbon feed direction to place the ribbon section about the filament, a welder in the path of movement of the filament opposite the ribbon section transporting head to weld the ribbon section to the filament, a cutter along the path of movement of the filament to cut through the ribbon section and filament, the filament feeding mechanism having jaws to engage the end of the ribbon section left by cutting off the leading end of the filament and movable to pull a new section of filament and attached ribbon section into the cutter mechanism, and means to operate the ribbon and filament feeding means, the ribbon deforming and cutting mechanisms, the ribbon transporting head, the welder and the filament cutter.

10 18. In a filament tabbing machine mechanism for longitudinally feeding a filament with spaced ribbon sections along the filament secured thereto, cutter mechanism to cut through the ribbon section and filament to form filaments with tabbed ends, said feeding mechanisms comprising a support spaced longitudinally from the cutter, jaws movable in said support toward the cutter to grasp a tabbed filament end in the cutter and to pull it toward the support, a turret having a vertical plate indexible on a horizontal axis and located between the cutter and the support, radial slides on said turret, a cam concentric with the horizontal axis engaging the inner ends of the slides, suction heads on the outer ends of said slides, valves controlling the suction to the head, cam controlled means for operating the feeding mechanism, the cutter jaws, the indexible turret, the concentric cam, and the valves for the suction head, suction to the head being terminated when the head reaches its lowest position and adapted to deposit a tabbed filament in a walled tray which may be placed beneath the turret.

15 19. A combined ribbon clamping, cutting and transfer mechanism for a ribbon intermittently fed to the mechanism comprising a frame block, a ribbon pressure pad slidably mounted on the block extending longitudinally of the block and the longitudinal length of the ribbon, a shear mechanism mounted on the block at the trailing end of the pad in the direction of intermittent movement of the ribbon and comprising a fixed cutter knife, a second cutter knife spaced longitudinally from the first knife, and a third knife movable in between the two knives to cut out a slug of ribbon from the length of ribbon to separate a ribbon section, a slide in the block supporting the third knife, means for operating the slide, means for operating the pad to hold the ribbon fixed while the cutter knives are operating said third knife having a bevelled face, in combination with a station having a means to receive a cut ribbon section, and transfer jaws adjacent the cutting mechanism adapted to receive the free end of the ribbon and operative to transfer the cut off ribbon section to said station, said jaws moving the just cut off end of the ribbon section along the bevelled face of the third knife as the transfer jaws move toward the station to center the ribbon with respect to the jaws and the station.

20 20. A combined ribbon clamping, cutting and transfer mechanism for a ribbon intermittently fed to the mechanism comprising a frame block, a ribbon pressure pad slidably mounted on the block extending longitudinally of the block and the longitudinal length of the ribbon, a shear mechanism mounted on the block at the trailing end of the pad in the direction of intermittent movement of the ribbon and comprising a fixed cutter knife, a second cutter knife spaced longitudinally from the first knife, adjustable slide means mounting the second knife for aligning the two knives, and a third knife movable in between the two knives to cut out a slug of ribbon from the length of ribbon to separate a ribbon section, a slide in the block supporting the third knife, means for operating the slide, means for operating the pad to hold the ribbon fixed while the cutter knives are operating said third knife having a bevelled face, in com-

21

bination with a station having means to receive a cut ribbon section, and transfer jaws adjacent the cutting mechanism adapted to receive the free end of the ribbon and operative to transfer the cut off ribbon section to said station, said jaws moving the just cut off end of the ribbon section along the bevelled face of the third knife as the transfer jaws move toward the station to center the ribbon with respect to the station.

21. A combined ribbon clamping, cutting and transfer mechanism for a ribbon intermittently fed to the cutting mechanism comprising a frame block, a ribbon pressure pad slidably mounted on the block, extending longitudinally of the block and the longitudinal length of the ribbon, a shear mechanism mounted on the block at the trailing end of the pad in the direction of intermittent movement of the ribbon, said shearing mechanism being operative on the ribbon to cut off a section thereof, said shearing mechanism including a knife with a cutting edge and a bevelled face remote from the cutting edge, a ribbon section receiving station, and transfer jaws adjacent the shearing mechanism adapted to receive the free end

10

15

20

22

of the ribbon and operative to transfer the cut off ribbon section to the receiving station, said jaws moving the just cut off end of the ribbon section along the bevelled face of the shearing mechanism as the transfer jaws move toward the receiving station to center the ribbon with respect to the jaws and the receiving station, and means for operating the pressure pad to hold the ribbon fixed while the shearing mechanism is operating.
